Albert E. Hammond,
Inventor.

By Atty.

UNITED STATES PATENT OFFICE.

ALBERT E. HAMMOND, OF PORTLAND, OREGON.

EVAPORATOR.

1,266,461.

Specification of Letters Patent. Patented May 14, 1918.

Application filed May 21, 1917. Serial No. 169,956.

To all whom it may concern:

Be it known that I, ALBERT E. HAMMOND, a citizen of the United States, residing in the city of Portland, county of Multnomah, and 5 State of Oregon, have invented certain new and useful Improvements in Evaporators, of which the following is a specification.

My invention relates to evaporators of the character designed for drying fruit, vegetables, and the like, and has as its principal 10 object to provide an improved construction and arrangement for evaporators, whereby a more uniform result can be secured in the drying of a large quantity of matter. In 15 order to explain my invention and to point out its improved features, I have illustrated one practical embodiment thereof in the accompanying two sheets of drawings, which I will now describe.

20 Figure 1 is a horizontal sectional view through an evaporator embodying my invention, with the middle portion broken out to reduce the size of the figure;

Fig. 2 is a side elevation thereof;

25 Fig. 3 is a vertical cross sectional view thereof taken on the line 3—3 of Fig. 2; and

Fig. 4 is an end view looking at the right hand end of Fig. 2.

Referring now more in detail to the drawings, 30 my invention comprises a housing, preferably of long rectangular form, having the side walls 1—1, a straight end wall 2, and the converging end walls 3—3, all of said walls being of double construction, whereby 35 to be filled with any suitable heat-retaining matter, as may be desired. Extending through the middle portion of said housing, longitudinally thereof, is a double-walled partition 4. In the straight end walls 2, I

40 have provided a series of narrow, transversely extending doors, as 5—5, which can be opened, as indicated at the right hand end of Fig. 2, for admitting air into said housing. At the opposite end of said housing,

45 I have provided a suction fan mechanism, designated as a whole 6, which may be of any usual construction, and the fan of which may be driven as by means of a driving pulley 7. Near the straight end of said housing

50 and adjacent the air inlet doors 5—5, I have provided a series of heating coils 8, shown in top plan view in Fig. 1, and in end view in Fig. 3, with supply pipe 9 leading thereto. Adjacent said heating coils I have provided

55 a curved air retarding distributing member 10, here illustrated as woven wire fabric,

although any open or perforated structure through which the air can pass may be used, said member operating to retard and more uniformly distribute the air as it passes 60 therethrough into the drying chamber. A similar member 11, is arranged at the fan end of the housing. It will be noticed that said members 10 and 11 are curved, whereby to operate more effectively in an even distribution of the air passing through the evaporator housing.

On opposite sides of the central partition 4, are car tracks 12 and 13, having at their ends turn tables 14, 15, 16 and 17, said turn tables being arranged at the junctures of said car tracks with transversely extending tracks 18 and 19, extending cross-wise through the housing, as indicated. Said housing is provided at said cross tracks with 75 doors 1^a—1^b, whereby cars 20—20, on which the matter to be dried is placed on any suitable supporting means thereon, can be run into and out of said housing.

From this construction and arrangement 80 it will be evident that cars of matter to be dried can be moved into said housing, for example, on the track 18, and then moved rearwardly on the track 12, to the track 19, and thence across the track 13 and back to 85 the track 18, thus passing the car of material to be dried slowly through the housing and turning it so that three sides of the car will, at different times be turned toward the end of the housing from which the heated air 90 comes. It will also be evident that the matter to be dried is first subjected to the lower heat, which increases as the car is moved rearwardly toward the heating end of the housing. The cars can either be removed 95 from the housing on track 19, or returned again to track 18, and removed from the housing. The movement and direction of the cars through the housing, of course, will depend upon the nature of the matter to be 100 dried and the length of time required to properly dry it. If desired, the matter to be dried can be run into the housing on track 19, and thus first subjected to the more intense heat and then moved along to the opposite end thereof where the heat is not so great.

Referring to Fig. 2 I have provided in the sides of the housing little windows 21, with slide covers therefor, which may be 110 used, if desired, for inspecting the matter to be dried without opening the larger doors.

1. By reaching through one of these little windows samples of matter being dried may be removed very conveniently.

Thus I have provided an improved evaporator of considerable length through which, in either direction, cars of matter to be dried can be moved, with means for passing them from one track to the other, and with means for removing said cars from either end of the housing, and while I have shown one practical embodiment of my invention I do not limit the invention to this particular form, except as I may be limited by the hereto appended claims.

15 2. I claim:

1. An evaporator of the character referred to comprising a housing of rectangular form provided at one end with means for admitting and heating air, and at its opposite end with means for causing a circulation of air through said housing, longitudinally-extending tracks in said housing, cross tracks extending through said housing near the opposite ends thereof, turn tables at the junctures of said longitudinal tracks with said cross tracks, whereby cars can be transferred from one track to the other, and air distributing and retarding means near the opposite ends of said housing.

30 2. An evaporator comprising a long rectangular housing provided at one end with means for admitting and heating air, and at its opposite end constructed with converging end walls, means operating at the converging ends of said end walls for causing a circulation of air through said housing,

curved air distributing and retarding means near the opposite ends of said housing, and car tracks arranged in said housing between said air retarding and distributing means 40 to receive cars of material to be dried, substantially as described.

3. An evaporator comprising a long rectangular housing having converging end walls at one end with means thereat for 45 causing a circulation of air through said housing, means at the opposite end of said housing for admitting air, means for heating said air as it enters said housing, car tracks extending longitudinally within said 50 housing, car tracks extending cross-wise through said housing, turn tables at the junctures of said cross tracks with said longitudinal tracks for turning and transferring cars from one track to another, and a curved air retarding structure across said housing adjacent the converging end walls thereof, substantially as described.

4. In an evaporator of the character referred to, a housing with converging wall 60 members at one end thereof, means for causing a circulation of air through said housing toward said converging walls, and a curved air retarding structure with air openings therethrough, arranged near the converging 65 end walls of said housing.

Signed at Portland, Multnomah county, Oregon, this 15th day of May, 1917.

ALBERT E. HAMMOND.

In presence of:

I. M. GRIFFIN,
J. C. STRENG.
